UNITED STATES PATENT OFFICE.

CHARLES H. GILL, OF CHICAGO, ILLINOIS.

STYLUS FOR SOUND-REPRODUCING MACHINES.

1,329,832.

Specification of Letters Patent.

Patented Feb. 3, 1920.

Application filed May 16, 1919. Serial No. 297,520.

To all whom it may concern:

Be it known that I, CHARLES H. GILL, a citizen of the United States, residing at Chicago, in the county of Cook and State of Illinois, have invented new and useful Styli for Sound-Reproducing Machines, of which the following is a specification.

My invention relates to improvements in styli or needles which are used in contact with sound records to convey the recorded vibrations to the sound reproducer for reproduction; and the objects of my improvement are, first, to provide a stylus having a multiplicity of points so that new points may be brought into operative position as required without the need of inserting a new stylus or needle so frequently; second, to provide supporting and attaching means for said stylus so as to make it available for use on sound reproducing machines of types now in use; third, to provide means for readily moving a new point into operative position at will and for indicating to the touch and hearing that such new point has been so moved to operative position; and, fourth, to provide means whereby further changes in the operative point are prevented after all the points on the stylus have been in use.

I attain these objects by the means illustrated in the accompanying drawing, in which—

Figure 1 is an enlarged front elevation showing my complete device assembled; Fig. 2 is an enlarged side elevation of the complete device, with the needle wheel shown in cross section; Fig. 3 is an enlarged side elevation, with the needle wheel shown in cross section, similar to Fig. 2, but with the needle wheel and clamping nut in removed position; and Fig. 4 is an enlarged front elevation of the needle wheel only.

Referring to the drawings, the needle wheel 11 consists of a disk portion and a number of radial pointed teeth 12, the wheel being also provided with a central opening 13 of circular form. In the illustrated construction, the teeth 12 are shaped to a point on all four of their sides but if very thin material is used in the construction of the needle wheel 11 the teeth 12 need be shaped to points only in the one direction as shown in Figs. 1 and 4.

The teeth 12 are so spaced apart that the needle wheel 11 can be placed edgewise upon a sound record at the correct playing angle

and have only one of the teeth 12 in operative contact with the record, the remaining teeth clearing the surface of the record.

A holding or supporting member for the needle wheel 11 is formed by the rod 14 which is bent at right angles near one of its ends. The end of this rod 14 opposite to the bent end is adapted to be inserted in the usual needle holding device on the reproducing member of a sound reproducing machine and to be fastened or secured in such needle holding device by the usual means, generally a set screw with a knurled head.

The bent portion of the rod 14 carries and is surrounded by a fixed disk 15 spaced away from its end and is threaded to receive an internally threaded nut 16. This nut 16 is provided with a disk part 17 and a knurled head 18 and is adapted to be screwed upon the threaded portion of the rod 14 and to frictionally secure the needle wheel 11 in position.

A pawl 19 is pivoted by means of a pin 20 to the upper part of the rod 14 and is pressed by the spring 21 which is secured upon the rod 14 by being bent around it and around the pin 20. The pawl 19 has a hook 22 on its angular face and one of the radial teeth 12 is provided with a notch 23 fitted to receive the hook 22 and lock the needle wheel against rotation in one direction whenever the hook 22 and the notch 23 are in operative proximity to each other.

In operation, the needle wheel 11 is placed upon the holding or supporting member, the threaded portion of the rod 14 passing through the circular opening 13 in the needle wheel 11. The pawl 19 is adjusted so that it is in the position shown in Fig. 1, being in contact with the reverse edge of the tooth 12 provided with the notch 23. The nut 16 is then screwed upon the threaded portion of the rod 14 so as to firmly press the needle wheel 11 between the fixed disk 15 and the disk part 17 of the nut 16, thus securing the needle wheel 11 against rotation and against any lateral movement. The knurled head 18 of the nut 16 is provided to make easier the screwing on and off of the nut.

The upper end of the rod 14 is now inserted in the opening of the needle holding device of the sound reproducing machine and the entire stylus is turned so that the flat sides of the needle wheel 11 are brought into line with the direction of the record

grooves on the sound record at the point of contact between stylus and record. The stylus is then made fast to the reproducing member of the sound reproducing machine in the same manner as an ordinary needle is secured in place, usually by means of a set screw. After one or more records have been played and it is desired to use a new stylus point, the nut 16 is slightly loosened and the needle wheel 11 is turned in the direction permitted by the pawl 19 until the said pawl falls into the next space between points. The new stylus point is now in operative position so the nut 16 is tightened. This operation is repeated as often as it is desired to use a new point until all have been used and the tooth provided with the notch 23 has been brought around to the position where the hook 22 on pawl 19 engages with the notch 23 and locks the needle wheel 11 against further rotation. This makes the operator aware that all the points have been used and that a new needle wheel should be inserted. It will be evident from the above that light is not necessary in changing points, the sense of touch and the click of the pawl in passing from one space between teeth to another being sufficient guides for the operation.

30 While I have described a specific con-

struction in the foregoing specification and in the drawing, I do not wish to be limited to such construction as it is evident that numerous departures may be made in the means employed without departing from 35 the spirit of this invention.

Having described my invention, I claim—

1. In a stylus for sound reproducing machines, the combination of a member having a multiplicity of stylus points, supporting 40 and locking means adapted to hold said member in such position that only one of said stylus points of said member will be in operative position at any time, means for bringing a new stylus point of said member 45 into operative position at will and means for preventing the bringing of a new stylus point of said member into operative position when all of said stylus points of said member have been in use. 50

2. In a stylus for sound reproducing machines, the combination of a star wheel adapted to have one of its teeth in operative position at one time and to be turned to bring an adjacent tooth into operative position at 55 will and means for preventing said turning after all of the teeth of said star wheel have been in use.

CHARLES H. GILL.
